UNITED STATES PATENT OFFICE.

JOHN G. HODGSON, OF MAYWOOD, ILLINOIS, ASSIGNOR TO AMERICAN CAN COMPANY,
OF NEW YORK, N. Y., A CORPORATION OF NEW YORK.

SPRAYING-MACHINE.

1,227,617.

Specification of Letters Patent.

Patented May 29, 1917.

Application filed May 5, 1913. Serial No. 765,570.

To all whom it may concern:

Be it known that I, JOHN G. HODGSON, a citizen of the United States, residing in Maywood, in the county of Cook and State 5 of Illinois, have invented a new and useful Improvement in Spraying-Machines, of which the following is a specification.

This invention relates to improvements in spraying machines, and more particularly to 10 machines for spraying the interiors of cans.

One object of the invention is to provide 15 a machine for spraying lacquer or other coating material on the walls of cans and can ends, so arranged that the spraying is controlled by the presence of the article to be coated.

Another object of the invention is to provide 20 a spraying machine having a carrier, intermittently rotated, which is provided with a plurality of constantly rotated can holding chucks successively brought into operative position relatively to the spraying devices.

Another object of the invention is to provide 25 a spraying machine so constructed that it is adapted to provide for either a single coating of the lacquer on the walls of the can or several coatings on each can, or to coat a plurality of cans simultaneously, the arrangement being such that several of the parts may be duplicated, thus in effect multiplying the capacity of the machine.

A still further object of the invention is to provide novel spraying devices, automatically controlled by the article being sprayed, said devices being adjustable as to height, inclination, and quality and quantity of the spray.

The invention furthermore consists in the 40 improvements in the parts and devices and in the novel combinations of the parts and devices as herein shown, described or claimed.

In the drawing forming a part of this 45 specification, Figure 1 is a part sectional, part elevational view of a spraying machine embodying my improvements, and Fig. 2 is a top plan view of the structure shown in Fig. 1, and illustrating also an additional 50 set of spraying devices in order to increase the capacity of the machine.

In said drawing, the base of the machine is designated by the reference 10, and on 55 said base are secured a standard 11 for the turret, hereinafter described, and a standard 12 for supporting the spraying devices A.

Mounted in the standard 11 is a vertical, intermittently rotatable shaft 13, driven by gears 14 and 15, the latter being secured to a horizontal shaft 16 intermittently rotated 60 as by the Geneva stop motion 17, 18, the latter member of the Geneva motion being mounted on a horizontal shaft 19 driven by gear 20 and pinion 21, the latter being secured to the power shaft 22 driven from any 65 suitable source of power (not shown) as by means of the pulley 23. Secured to the upper end of the shaft 13 is a carrier 24 on which are mounted a plurality of chuck holding brackets 25, each chuck holding 70 bracket having rotatably mounted therein, a magnetized chuck 26 having a spindle 27 to which is secured a bevel pinion 28, all of said bevel pinions 28 being constantly rotated by a bevel gear 29 loosely rotatably 75 mounted on the shaft 13 and driven by the bevel gear 30 and 31, the latter being secured to the inner end of the shaft 22. The axis of each chuck is inclined from the vertical, whereby the running of the liquid 80 coating down to the bottom of the can is retarded while it is being distributed around the cylindrical walls of the can by the rotation of the chuck. Such inclination of the can, together with its axial rotation, also 85 promotes the distribution of the coating evenly over the bottom of the can. Each chuck 26, as more clearly shown in Fig. 1, is recessed to thereby receive and properly center the cans 32 or other articles to be operated upon, and slidably mounted in each of the chuck spindles 27 is an ejector or knock-out rod 33 operated by a stationary cam 34 so located that the cans are ejected after the spraying operation has taken place. 95

Adjustably mounted in the standard 12, as by means of set screws 35 is a rod 36 having pivotally mounted thereon, at its upper end, a supporting bracket 37, having arms 37^a and 37^b. The lower arm 37^a of the 100 bracket 37 has pivotally and adjustably secured thereto, a lacquer supply tank 38 adapted to be supplied with the lacquer or other coating material through an inlet pipe 39. As shown in Fig. 2, the tank 38 is 105 formed on the arc of a circle and carries a pair of adjustably mounted tubes 40 which have their lower ends projecting down into the lacquer, and their upper ends arranged in proximity to compressed air pipes 41, the 110 latter being adjustably mounted in brackets 42 pivotally and adjustably mounted on the

upper arm 37^b of the bracket 37. The pipes 41 are connected to any suitable source of compressed air (not shown) and the supply of air in each pipe 41 is controlled by a 5 valve 43, lever 44, link 45 and controlling lever 46, the latter at its inner end carrying a roller 47 adapted to be engaged and operated by the cans or other vessels against the action of a spring 48. Any sliding of 10 the can on the magnetized chuck surface, which might be caused by the resistance of the spring 48 or the valve mechanism, is prevented by a suitable stop, which is in this instance formed by the flange of the chuck 15 26, within which flange the can is seated. Each controlling lever 46 is pivotally mounted on a stationary arm 49 secured to the bracket 37.

In Fig. 2, two sets of spraying devices 20 are shown suitably arranged around the circumference of the rotating carrier 24, so that both sets of spraying devices may operate simultaneously on different sets of cans, the latter being fed preferably by hand 25 on to the chucks by two operators just prior to the chucks reaching the spraying devices.

The number of chucks mounted on the carrier 24, as shown in the drawing, is 16, and the Geneva stop motion is so arranged 30 that the carrier is given an eighth of a revolution between stops so that two cans will be sprayed simultaneously. But it will be understood that by changing the Geneva stop so as to give the carrier only one- 35 sixteenth of a revolution for each stop, each can would be sprayed twice, and as will be apparent to those skilled in the art, the number of cans sprayed at one time or the number of coatings applied to each can, may 40 be varied as desired by either diminishing or increasing the number of spraying devices, and by changing the Geneva stop motion. In some instances it might also be desirable to spray the articles carried by the 45 chucks by using hand operated spraying devices.

As more clearly shown in Fig. 1, the cans are presented to the spraying devices at an 50 inclination to the vertical, thereby insuring a uniform application of the spray over 55 the entire inner walls of the cans which are constantly rotated while the spray is being applied, and by adjusting the parts of the spraying devices either as to height, inclination or relative positions of the lacquer pipes and air pipes 40 and 41 respectively, the size and quality of the spray may be 60 varied as desired.

The vertical adjustment of the spraying 65 device bodily by means of the sliding rod 36 accommodates the machine to cans of different height, and also, by regulating the diameter of the spray where it impinges, to cans of different diameters of opening. The 70 spray itself is properly produced by adjust-

ing the angle of the pipes 40, 41 to each other, which is done by turning one or both of the angularly adjustable extremities of the bracket arms 37^a, 37^b; and the spray is further regulated by longitudinally adjusting the pipe 40 toward or from the axis of the pipe 41 and by similarly adjusting the pipe 41 toward or from the axis of the pipe 40. After such bodily adjustment and regulation of the spray, the spray as a 75 whole is focused on the can by an up or down angular adjustment of the bracket 37.

Although I have herein shown and described what I now consider the preferred embodiment of my improvements, yet it will 80 be obvious to those skilled in the art, that various changes and modifications may be made without departing from the spirit of the invention, and all such changes and modifications are contemplated as come 85 within the scope of the claims appended hereto.

I claim:—

1. A spraying machine for cans and other articles including, in combination: a carrier rotatable about an axis and having a plurality of rotatable chucks mounted thereon; a spraying device to which the articles are brought successively by the movement of the carrier and its chucks; a spray controlling valve having means whereby it is actuated by the articles as the latter arrive opposite to the spraying device; and holding means on the chucks whereby the said articles are removably 100 fixed thereon and enabled to operate said valve actuating means.

2. A spraying machine of the character described including, in combination: a carrier intermittently rotatable about a vertical axis; a plurality of rotatable chucks on inclined axes carried by said carrier; and a stationary spraying device located adjacent the carrier and to which articles carried by said chucks are presented successively; substantially as specified.

3. A spraying machine of the character described including, in combination: a carrier rotatable about a vertical axis; a plurality of rotatable chucks carried by said carrier, each chuck being magnetized and constantly inclined relatively to the vertical; and a stationary spraying device to which the articles carried by said chucks, are adapted to be presented, substantially as 115 specified.

4. A spraying machine of the character described including, in combination: a carrier rotatable about a vertical axis and having a plurality of rotatable chucks mounted thereon each having means for securely and removably holding a can in place and enabling the same to actuate the spraying device; a stationary spraying device to which the articles are brought successively by the 125 130

- chucks on the carrier; and a can-governed means controlling the operation of said spraying device, substantially as specified.
5. A spraying machine of the character described including, in combination: a carrier intermittently rotatable about a vertical axis; a plurality of rotatable chucks carried by said carrier each having means for securely and removably holding a can in place to actuate the spraying device; a stationary spraying device located adjacent the carrier and to which articles carried by said chucks are presented successively; and can-governed means controlling the operation of said spraying device, substantially as specified.
6. A spraying machine of the character described including, in combination: an intermittently rotatable carrier; a plurality of rotatable magnetized chucks carried by said carrier and having means for inclosing a part of the can and holding the can from lateral displacement; a stationary spraying device arranged adjacent said carrier in front of which the articles to be sprayed are brought when the carrier is at rest; and automatically operable means for controlling the operation of said spraying device, substantially as specified.
7. A spraying machine of the character described including, in combination: a carrier intermittently rotatable about a vertical axis; a plurality of rotatable recessed and magnetized chucks carried by said carrier; a stationary spraying device to which the articles carried by said chucks are brought to be coated comprising a longitudinally adjustable liquid pipe and a longitudinally and angularly adjustable air pipe; and means for vertically adjusting said spraying device, substantially as specified.
8. A spraying machine of the character described including, in combination: a carrier intermittently rotating about a vertical axis; a plurality of continuously rotatable recessed and magnetized chucks carried by said carrier; a stationary spraying device comprising a longitudinally adjustable liquid pipe and a longitudinally and angularly adjustable air pipe; and means for angularly adjusting said spraying device, substantially as specified.
9. A spraying machine of the character described including, in combination: a carrier rotatable about a vertical axis; a plurality of rotatable recessed and magnetized chucks carried thereby; a vertically adjustable stationary spraying device to which the articles carried by said chucks are presented successively comprising a longitudinally adjustable liquid pipe and a longitudinally and angularly adjustable air pipe; and means for angularly adjusting the spraying device, substantially as specified.
10. A spraying machine of the character

described including, in combination: a carrier rotatable about a vertical axis having a plurality of chuck holding brackets secured thereto; magnetized chucks having means to engage the side of the can and rotatably mounted in said brackets; means for rotating the chucks on said carrier, said means including a bevel pinion carried by each of said chucks and a common rotatable bevel gear meshing with said pinions; and means for rotating said carrier, substantially as specified.

11. A spraying machine having a spraying device comprising a tank, a bracket on which said tank is adjustably mounted, a compressed air pipe, said pipe being adjustable longitudinally and angularly, a pipe projecting within said tank and having its outer end placed adjacent the end of the air pipe, and means engageable by the article being sprayed for controlling the supply of air through the air pipe, substantially as specified.

12. In a spraying machine, a spraying device including a standard, a supporting bracket vertically adjustably mounted in said standard, a tank carried by said bracket, a compressed air pipe carried by said bracket and adjustable longitudinally and angularly, and automatically operated means engageable by the article being sprayed for controlling the supply of air in said pipe, substantially as specified.

13. In a spraying machine, a spraying device comprising a supporting bracket, a supply tank angularly, adjustably mounted on said bracket and having a longitudinally adjustable liquid pipe, a compressed air pipe angularly adjustably mounted on said bracket, and automatically operated means engageable by the article being sprayed for controlling the air supply in said pipe, substantially as specified.

14. A spraying machine of the character described including, in combination: a carrier intermittently rotatable about a vertical axis; a plurality of chucks rotatably mounted on said carrier; a plurality of stationary spraying devices arranged around the periphery of said carrier and simultaneously spraying alternate cans, substantially as specified; and means for actuating said carrier to cause alternate cans to pass one of said spraying devices without intermission.

15. In a can-spraying machine, in combination: an intermittently rotatable carrier; can-holding rotary chucks on said carrier the axes of which are inclined from the vertical; and an intermittently acting spraying device having its line of delivery arranged to enter the open end of the can at an angle to the axis of the can.

16. In a can-spraying machine, in combination: an intermittently rotatable carrier; can-holding rotary chucks on said carrier

- the axes of which are inclined from the vertical; and an intermittently acting spraying device having its line of delivery arranged to enter the open end of the can at an angle 5 to the axis of the can, the said chucks being magnetized to hold the cans to their faces and having means to engage the sides of the cans to hold them from lateral displacement.
- 10 17. In a can-spraying machine, in combination: a rotatable carrier having arranged thereon at certain intervals a series of rotary can-holding chucks; a plurality of spraying devices each arranged to spray a 15 can when the latter is brought opposite to it, the said devices acting on alternate cans; and means for turning the said carrier step by step, each of which steps is equal to the interval between the first and last sprayed 20 cans plus the interval between two contiguous cans, each alternate can passing without pause in front of one spraying device, and the other alternate cans passing without pause in front of the other spraying device.
- 25 18. A can spraying machine including, in combination: a carrier rotatable about a ver-

tical axis and having a plurality of rotatable chucks mounted thereon; a spraying device to which the cans are brought successively by the movement of the carrier and its 30 chucks; a spray controlling valve having means whereby it is actuated by the sides of the cans as the latter arrive opposite to the spraying device; and holding means on the chucks whereby the cans are removably 35 fixed thereon and enabled to operate said valve and actuating means.

19. In a spraying machine of the character described, for coating cans and other articles, in combination: a carrier rotatable 40 about an axis; means for intermittently rotating said carrier; a plurality of rotatable chucks mounted on said carrier and having their axes outwardly inclined; each chuck having a recess in which a can is adapted to 45 be securely seated; and means whereby said chucks are magnetized to hold the base of the can within said recess.

JOHN G. HODGSON.
